UNITED STATES PATENT OFFICE.

DAVID F. CURTIN, OF CHICAGO, ILLINOIS.

HOLDER FOR SODA-CUPS AND THE LIKE.

1,280,416.

Specification of Letters Patent.

Patented Oct. 1, 1918.

Application filed June 3, 1914. Serial No. 842,871.

To all whom it may concern:

Be it known that I, DAVID F. CURTIN, a citizen of the United States, and a resident of Chicago, in the county of Cook and State 5 of Illinois, have invented a new and useful Improvement in Holders for Soda-Cups and the like, of which the following is a specification.

My invention is an improvement in holders for soda cups and the like, and has for 10 its object to provide a rigid holder for use in soda fountains and like places, wherein a holder proper is provided supported by a base, the holder proper being of conical 15 shape and having an inwardly offset lip or tongue for engaging a lip or tongue on the blank to hold the blank in place.

In the drawings:

Figure 1 is a perspective view of the 20 holder and a container for the blanks, showing the manner of picking up the blanks from the container by the holder.

Fig. 2 is a front view of the holder with the blank in place,

Fig. 3 is a perspective view of the same 25 with parts in section, and

Fig. 4 is a section on the line 4—4 of Fig. 2.

The present embodiment of the invention 30 comprises a holder proper or body 1 of frusto-conical shape and arranged with its small end downward, and the large end of the holder proper is beaded as shown at 2. The lower small end of the holder proper 35 is continuous with a column or standard 3 of tubular form, and the lower end of the standard is connected to a circular base 4.

In the present instance, the base is 40 grooved on its under face near its periphery to form an annular rib 5 on the upper face for the purpose of reinforcing and strengthening the base. The body 1 of the holder is shaped to fit a cone having a lateral area three-fourths of the area of the circle 45 the radius of which is the slant length of the cone. That is, the holder is shaped to fit and receive conical cups made from blanks of circular shape by forming one-fourth of the area of the blank into a tongue 50 or lip.

The body of the holder is provided with an inwardly offset tongue 6, the tongue in the present instance being formed by slitting the material of the body on lines 55 parallel and spaced apart from each other

and connected at one end, the material between the lines being offset inwardly as shown more particularly in Fig. 4.

The blanks forming the subject-matter of my above-mentioned co-pending application 60 are formed from disks of paper, creased on two lines extending from the center to the periphery at an angle of 45° with respect to each other.

The blank 7 is bent in opposite directions on these lines, and that portion of the blank between the two lines is folded on to the outer surface of the blank to form a tongue, lap or lip 8, the said tongue or lip extending from the center to the 70 periphery of the blank.

The tongue or lip 8 of the blank is engaged beneath the tongue or lip 6 of the holder to hold the blank in place, the blank being formed into a cup by the bend above mentioned. The blank is of such size that when in place in the cup a portion of the blank will extend beyond the bead 2 of the holder as indicated at 9 in Figs. 2 and 3 to protect the edge of the holder proper. 80

The apex of the cup formed by folding the blank is received in the hollow stand or column 3 of the holder. In practice the blanks folded as above mentioned in cup shape are arranged within a container comprising an approximately cylindrical body 10, having its upper edge beaded as shown at 11, and provided with an opening 12, extending from the top to the bottom of the body. 85

A bottom 13 is provided for the container, and the cups 7 formed by folding the blanks are nested, and are then placed in the container in inverted position as shown in Fig. 1. 90

When it is desired to use one of the cups formed by the folding of the blanks, the holder is grasped by the base as shown in Fig. 1 and placed in position over the uppermost blank. The holder is then partially rotated to cause the tongue or lip 6 to enter beneath the tongue or lip 8 of the blank, and the cup may then be lifted out of the container in proper position in the holder. 100

After using the cup may be easily dislodged from the holder by giving it a partial rotation to release the tongue 8 from the tongue 6 of the holder. The blank may be of any desired size and it is obvious that it is not essential to fold one-fourth of the 110

area into the tongue. It is only necessary to fold enough of the blank to form a tongue of some character.

The folding of one-fourth of the blank 5 makes a good size cup, having about the proper capacity and holding the contents in easily accessible position. By folding less of the blank into the tongue, a deeper 10 cup is obtained while by folding more a shallower cup will result.

Should the cup stick in the holder through adherence between the outer surface of the cup and the inner surface of the holder it may be easily dislodged through the tubular 15 column for the said column opens through the base.

I claim:—

1. A holder for folded paper cups of conical shape comprising a frusto-conical body 20 arranged with its small end downward and open, a base of circular form and a tubular column connecting the small end of the body with the base, said base having an opening at the column, and the body having a portion 25 of the wall thereof partially separated and offset inwardly to form a tongue for engaging the fold of the cup.

2. A holder for folded paper cups of conical shape comprising a frusto-conical body 30 arranged with its small end downward and open, and a base connected to the small end of the body, a portion of the wall of the body being partially separated and offset 35 inwardly to form a tongue for engaging the fold of the blank.

3. A holder for folded paper cups of conical form comprising a body formed to fit the exterior of said cup and having an aper-

ture in its side intermediate its height, a base 40 rigidly connected to the small end of said body and a tongue attached to said body and projecting over said aperture for engaging a fold of said cup to hold the cup in contact with said body and permit the extent of said engagement to be seen from the exterior of said body.

4. A holder for paper cups of conical form comprising a body part formed to fit the exterior of said cup, having an aperture 5 in its side intermediate its height, and a base rigidly connected to the small end of said body part by a tubular standard rigidly connected to said base and body part, and a resilient tongue spaced inward from the inner face of said body part rigidly secured thereto and projecting over said aperture for engaging a fold of said cup to hold the cup in contact with the body and permit the extent of said engagement to be seen from the exterior of said holder. 60

5. A holder for folded paper cups of conical form, comprising a body formed to fit the exterior of said cup, a base connected to the small end of said body, and a tongue 65 attached to said body intermediate its height, and extending circumferentially of the body, and adapted to engage a fold of the cup to hold the cup in contact with the body and to permit the cup to be received in the container without the necessity of touching said cup. 70
